UNITED STATES PATENT OFFICE.

JOHN GOODMAN, OF LOUISVILLE, KENTUCKY.

TELEPHONE.

SPECIFICATION forming part of Letters Patent No. 243,883, dated July 5, 1881.

Application filed April 28, 1881. (No model.)

To all whom it may concern:

Be it known that I, JOHN GOODMAN, a citizen of the United States, resident at Louisville, in the county of Jefferson and State of Kentucky, have invented a new and valuable Improvement in Instruments for the Production and Reproduction of Sounds by Means of an Electric Current; and I do hereby declare that the following is a full, clear, and exact 10 description of the construction and operation of the same, reference being had to the annexed drawings, making a part of this specification, and to the letters and figures of reference marked thereon.

15 Figure 1 of the drawings is a representation of the instrument in its simplest form, (diagrammatic.) Fig. 2 is a sectional view of a more perfect instrument.

The present invention has relation to that 20 class of instruments by means of which sounds, articulate and otherwise, are produced or reproduced through the agency of electricity at a distance from the transmitting station.

In a prior Patent, No. 234,578, November 30, 25 1880, I described one form of instrument of this kind based upon the principle of the ordinary galvanometer—that is, in which the resonator or diaphragm is thrown into vibration by means of a magnet in combination 30 with a conductor of electricity or helix, the two bearing such a relation to each other that when a current of electricity is passed through the conductor the magnet will tend to assume a position at right angles therewith. I now 35 present and desire to obtain Letters Patent for another form of this instrument.

In the accompanying drawings, Fig. 1 is 40 a diagrammatic representation of the simplest form of the instrument under consideration. C is a sectional view of a flattened helix. D is a magnet pivoted at its center, the pivot being passed through a hole in the center of the helix. B is a diaphragm or resonator, and

R is a delicate rod connecting the diaphragm with the magnet. If elastic pressure were 45 brought to bear upon any part of the magnet, so as to press it toward or from the diaphragm, the instrument would come within the class already described by me in the patent alluded to. The relative position of the different parts 50 of this instrument may be altered without affecting the fundamental principles of its construction.

Fig. 2 represents a sectional view of a more perfect form of the instrument. F is a case, of 55 wood, rubber, or composition. C is a sectional view of a flattened helix. D and D' are magnets arranged in two series, with like poles toward the central line of the helix. A and A' are ear-pieces. B and B' are diaphragms, one 60 at each end of the instrument; and R is a connecting rod, cord, or wire extending from one diaphragm to the other, to which the magnets are attached at the central line of the helix. The second diaphragm being actuated synchronously with the first, and the movements 65 being in the same direction, the sound is thereby intensified.

I claim—

1. A conductor and a centrally-pivoted magnet arranged parallel therewith, in combination with a diaphragm and means for connecting the magnet to the diaphragm, substantially as set forth. 70

2. A conductor and a centrally-pivoted magnet arranged parallel therewith, in combination with two diaphragms and means for connecting said diaphragms to the magnet, substantially as set forth. 75

In testimony that I claim the above I have 80 hereunto subscribed my name in the presence of two witnesses.

JOHN GOODMAN.
